George McFarland
Atty.

UNITED STATES PATENT OFFICE.

GEORGE McFARLAND, OF PEORIA, ILLINOIS, ASSIGNOR TO McFARLAND COMPANY, OF PEORIA, ILLINOIS, A CORPORATION OF ILLINOIS.

MANIFOLD.

1,249,647.

Specification of Letters Patent. Patented Dec. 11, 1917.

Application filed March 27, 1916. Serial No. 86,949.

To all whom it may concern:

Be it known that I, GEORGE McFARLAND, a citizen of the United States, and resident of Peoria, in the county of Peoria and State 5 of Illinois, have invented certain new and useful Improvements in Manifolds, of which the following is a full, clear, and exact description, reference being had to the accompanying drawing, forming part of this specification.

10 My invention relates primarily to manifolds for use on internal combustion motors where it is desired to employ kerosene as a fuel.

15 The object of my invention is to provide a manifold by means of which the engine can be started on gasoline as a fuel and whereby when the engine has become heated, the fuel may be changed from gasoline to kerosene and the operation of the engine continued successfully.

20 Further objects of my invention will be referred to and described as the specification proceeds.

25 The novelty of my invention will herein-after be more fully set forth and specifically pointed out in the claims.

In the accompanying drawing;

30 Figure 1 is a sectional plan view of a manifold embodying my invention, taken on the dotted line 1—1 of Fig. 2.

Fig. 2 is a sectional side elevation of the manifold taken on the dotted line 2—2 of Fig. 1.

35 Fig. 3 is a sectional end view taken on the dotted line 3—3 of Fig. 2.

The same numerals of reference are used to indicate identical parts in all the figures.

40 The manifold consists, as shown, of a box-like structure 1, forming a cavity to receive the exhaust gases through the ports 2, which register with the exhaust ports of the cylinders of any suitable engine, not shown.

45 An exhaust outlet 3, is provided, and the usual exhaust pipe is connected to this exhaust outlet.

An intake passage 4, which is formed integral with the manifold, lies within the exhaust cavity and leads from a connecting 50 surface 5, to which any suitable carburetor may be connected, to ports 6, which register with suitable intake ports of the cylinders of an engine.

The structure shown is intended primarily for use on a four cylinder engine, though by 55 modification it could be equally well adapted to any other number of cylinders. The lower wall of the intake passage 4, as shown clearly in Fig. 2 is inclined from the ports 6 to the surface 5 in such manner that any 60 liquid particles of fuel will drain back to the carburetor and will not collect in the intake passage.

It will also be observed that the intake passage partly overlaps a part of two of the 65 exhaust ports in such manner that the exhaust gases will impinge directly on the side and top wall of the intake passage before these gases have expanded to a point which will materially reduce their temperature, 70 thereby heating the side and top wall of the intake passage so that the entering fuel, by striking this heated portion, will be thoroughly gasified.

It is well known that if hot compressed 75 gases are permitted to expand the temperature of these gases drops very rapidly. By placing the intake passage 46 as to partly overlap one or more of the exhaust ports so that part of the flame on entering the exhaust cavity strikes the side wall while the balance strike the top wall to heat the intake passage directly above the inlet port thereof, I am enabled to sufficiently heat this passage to thoroughly vaporize the particles of kerosene while they are passing through.

To afford an easy and convenient method of attaching the manifold to the cylinders, I provide cored lugs 7 through which studs 90 or bolts may pass to said cylinders.

Having thus fully described my invention, I claim:

1. A combined intake and exhaust manifold comprising in part an outer wall said 95 manifold being provided with a series of exhaust ports opening into an exhaust cavity, an inlet passage partly formed by the outer wall above mentioned and lying entirely within the exhaust cavity and having part 100 of its length partly opposite at least one of said exhaust ports in such manner that the stream of exhaust gases on entering the exhaust cavity will be divided by said inlet passage and caused to flow partly over the 105 top of said passage and partly down the

side, an inlet port opening into said passage, and outlet ports opening from said passage.

2. A combined intake and exhaust manifold comprising a box-like structure, having an outer wall, an inlet passage formed integral therewith, connections from said inlet passage to the wall opposite said outer wall,

an inlet port opening into said inlet passage, and exhaust ports opening into the exhaust cavity of the manifold in such way ¹⁰ that the projected area of at least one of said exhaust ports will intersect the inner surface of part of said inlet passage.

GEORGE McFARLAND.
